COUPLING NONTERMINAL ALLYLIC HALIDES

Irving D. Webb, Wilmington, Del., assignor to
E. I. du Pont de Nemours and Company, Wil-
mington, Del., a corporation of Delaware

No Drawing. Application March 25, 1950,
Serial No. 151,985

12 Claims. (Cl. 260—615)

1

This invention relates to a process for coupling non-terminal organic allylic halides. It also relates to a process for preparing unsaturated dialkoxy compounds by reacting ethers, containing non-terminal allylic halogen, with nickel carbonyl. This invention relates more particularly to a process for the preparation of 1,10-dimethoxy-decadiene-3,7.

It was known heretofore that certain allylic halides react with nickel carbonyl to form nickel halides and diallylic compounds (Belgian Patent 448,884; Chem. Abstracts 41:6576). It was not known heretofore, however, that allylic halides in which allylic halogen is not terminal could be coupled in this manner by the action of nickel carbonyl to give products coupled predominantly in the terminal positions rather than through the carbons initially carrying the halogen. Furthermore, this coupling reaction has not been employed heretofore in the preparation of dimethoxydecadiene from the methoxychloropentenes which are formed by reaction between chloromethyl ether and butadiene.

An object of this invention is to produce long chain compounds from relatively shorter chain allylic compounds. Another object is to prepare a long chain aliphatic ether having alkoxy groups in the terminal positions. A more specific object of the invention is to prepare 1,10-dimethoxy-decadiene-3,7. Other objects of the invention will appear hereinafter.

It has been discovered in accordance with this invention that non-terminal allylic halides are converted by the action of nickel carbonyl to products which are formed by coupling of terminal carbon atoms of the allylic halide rather than by coupling of the carbon atoms which were initially attached to the allylic halogen.

It has been discovered, for example, that 1,10-dialkoxydecadienes-3,7 can be prepared very readily by subjecting 3-chloro-5-alkoxypenten-1 to the action of nickel carbonyl. This reaction takes place at ordinary temperatures and pressures. If desired, an inert solvent (e. g. water or an inert organic diluent, or a mixture of such diluents) may be used. The nature of the inert organic diluent is not at all critical, suitable diluents being aromatic hydrocarbons, aliphatic hydrocarbons, dialkyl ethers, alkanols, alkanic acids, esters, and the like. A convenient solvent which may be used effectively in the practice of the invention is methanol.

Suitable non-terminal allylic halides which may be employed in the practice of the invention include 3-chloro-1-butene, 3,6-dichloro-5-ethoxy-1-hexene, 3-chloro-1-pentene, etc.

2

The reaction whereby the coupling of these halides occurs may be illustrated as follows:

5 1-chloro-5-methoxypenten-2

10 1,10-dimethoxydecadiene-3,7

15 3-chloro-5-methoxypenten-1

In practicing the invention it is generally preferred to employ a temperature within the range of 0° C. to 150° C., excellent results being obtained at temperatures within the range of 10° C. to 75° C.

20 One mol of nickel carbonyl is consumed, and one mol of nickel halide is produced for each mol of dimethoxydecadiene formed in the process above illustrated. It is generally highly desirable to employ substantial quantities of nickel carbonyl, preferably at least about 0.5 mol of nickel carbonyl per mol of the halide reactant.

The invention is illustrated further by means of the following example.

Example 1.—Into a mixture containing 200 cc. 30 butadiene, 1 gram hydroquinone, and 5 grams anhydrous zinc chloride at 10° C. was introduced 190 grams of chloromethyl ether with stirring after which the stirring was continued for four hours. The resulting mixture was permitted to 35 remain overnight in a sealed container at a temperature of 5° C. The mixture was then poured on ice, and the organic layer was separated. This was washed with water and dried by means of anhydrous potassium carbonate. Distillation of the resulting mixture gave about 100 cc. of 3-chloro-5-methoxypenten-1, B. P. 60°—62° C./39 mm. and about 75 cc. of 1-chloro-5-methoxypenten-2, B. P. 81°—83° C./35 mm. One hundred fifteen grams of the 3-chloro-5-methoxypenten-1 40 isomer in 200 cc. methanol was maintained under nitrogen pressure while a solution of 110 cc. nickel carbonyl and 400 cc. methanol was introduced. The mixture was maintained at a temperature of about 50°—60° overnight in a reaction flask which was equipped with a reflux condenser. The next day the methanol was distilled from the mixture at atmospheric pressure, and the residue was extracted with low molecular weight mixed alkanes to separate the organic material from 45 nickel chloride. The organic extract was then washed with water to remove the traces of nickel 50

chloride which remained. Upon evaporation of the solvent and distillation of the residue under diminished pressure, a fraction consisting predominantly of 1,10-dimethoxydecadiene-3,7, B. P. 138°-142° C./25 mm., was obtained (weight 69 grams, N_D^{27} 1.4505). The infra-red absorption curve for this material showed that it did not contain appreciable terminal unsaturation. The 1-chloro-5-methoxypenten-2 isomer was treated in the same manner and gave the same 1,10-dimethoxydecadiene-3,7 (B. P. 120°-125° C./14 mm., N_D^{30} 1.4492-1.4500) in excellent yield, and the infra-red absorption spectrum was identical to that obtained above.

Example 2.—3-chloro-1-butene, B. P. 63°, $N_D^{23.5}$ 1.4143 (after separation from its isomer, crotyl chloride, both of which were prepared by addition of hydrogen chloride to butadiene) was heated for several hours with a slight excess of nickel carbonyl at about 50° C., and the product was distilled. From 330 grams of 3-chloro-1-butene, the yield of octadienes was 150 grams (72%). By fractional distillation with a 4 ft. Podbielniak still column at 60/1 reflux ratio, the octadienes were found to contain 80%±2% of 2,6-octadiene (dicrotyl) and 20%±2% 3-methyl-1,5-heptadiene. No 3,4-dimethyl-1,5-hexadiene was found. The 2,6-octadiene thus obtained had the following properties: B. P. 125° C., N_D^{20} 1.4312. (Henne, Chanan and Turk, J. A. C. S. 63, 3474 (1941) reported B. P. 124.5°, N_D^{20} 1.4336). The 3-methyl-1,5-heptadiene thus obtained was also identified by its physical properties, B. P. 112.5° C., N_D^{20} 1.4240; (the previously reported values (Henne et al.) were B. P. 111° C., N_D^{20} 1.4240).

Example 3.—3,6-dichloro-5-ethoxy-1-hexene was separated from its isomer by fractional distillation and had the following properties: B. P. 50°-60°/0.3 mm., N_D^{25} 1.4622 (Pudovik, Izvest. Akad. Nauk. S. S. R. Otdel. Khim. Nauk 529-35 (1948) No. 5 Sept.-Oct., gives B. P. 81-2°/3 mm., N_D^{20} 1.4617). Seventy grams of this essentially pure isomer and 200 ml. methanol were treated slowly with stirring at 25-30° C. with 45 grams nickel carbonyl (50% excess of the stoichiometric). After standing overnight the solution was diluted with water and the organic phase was separated with the aid of petroleum ether. The product was vacuum distilled from a few grams CaCO_3 , and the distillate, B. P., 45-172°/1 mm., (largely 155-60°/1 mm.), was fractionated to separate unreacted starting material. The latter was removed as a cut to 109°/0.3 mm.; the remainder (45 grams, N_D^{26} 1.4740) was subjected to infra-red absorption analysis. The spectrum was identical with that of the coupled product from 1,6-dichloro-5-ethoxy-2-hexene (Tabet, U. S. Patent No. 2,570,886), and showed a strong absorption band at 10.35 microns but no absorption band at 10.03 microns and only very weak absorption bands at 6.0 microns and 10.95 microns. These data show that the product was predominantly 1,12-dichloro-2,10-diethoxy-4,6-dodecadiene, i. e. that only very little branched chain product containing the $-\text{CH}=\text{CH}_2$ group ing was present.

Example 4.—3-chloro-3-methyl-1-butene was prepared by low temperature (-50° C.) addition of hydrogen chloride to isoprene and was separated from its isomer by fractional distillation (B. P. 38-41° C./190 mm., N_D^{21} 1.4189). Coupling of 222 grams of this isomer was carried out using 220 grams nickel carbonyl (20% excess) and 300 ml. methanol at ordinary temperature. The

product was mixed with CaCO_3 and was distilled. The distillate, 107 grams, was redistilled with a 4 ft. Podbielniak still column at 60/1 reflux ratio. Only two flats appeared: (1) B. P. 143-150°, N_D^{20} 1.4368-1.4405, 40 ml.; this appears to be $(\text{CH}_3)_2\text{C}=\text{CCH}_2\text{C}(\text{CH}_3)_2\text{CH}=\text{CH}_2$ (Henne and Chanan, J. A. C. S. 66, 392 (1944), give B. P. 149.7° C., N_D^{20} 1.4391); (2) B. P. 162-164°, N_D^{20} 1.4516-1.4556, 80 ml.; this evidently was another isomer, possibly

although the refractive index was somewhat higher than the previously reported value for that particular isomer (Henne and Chanan give B. P. 168.6° C. N_D^{20} 1.4478).

It is significant that the rearrangements which occur in coupling non-terminal allylic halides by reaction with nickel carbonyl evidently are due, in part, to a specific influence of nickel carbonyl. Other coupling agents have been known to produce mixtures (J. A. C. S. 67, 841 (1945)), which, evidently, do not contain predominantly the straight chain isomers.

The products obtained in the practice of this invention are valuable as intermediates for the manufacture of resin chemicals, etc. For example, the 1,10-dialkoxydecadienes obtained in the practice of this invention are especially valuable as intermediates for the manufacture of dibasic acids, since hydrogenation of these dialkoxydecadienes yields dialkoxydecanes which in turn can be converted to sebacic acid by oxidation.

I claim:

1. The process which comprises coupling terminal carbon atoms of an organic compound containing non-terminal allylic halogen by reaction with nickel carbonyl, and separating from the resulting mixture the compound formed by the coupling of the said terminal carbon atoms.

2. The process of claim 1 in which the said reaction is carried out at a temperature of 50° to 150° C.

3. The process of claim 1 in which the said halogen is chlorine.

4. The process of claim 3 in which the said organic compound containing non-terminal allylic chlorine is 3-chloro-5-methoxypenten-1.

5. The process of claim 3 in which the said organic compound containing non-terminal allylic chlorine is 3-chloro-1-butene.

6. The process of claim 3 in which the said organic compound containing non-terminal allylic chlorine is 3-chloro-3-methyl-1-butene.

7. A process for preparing 1,10-dimethoxydecadiene-3,7 which comprises subjecting 3-chloro-5-methoxypenten-1 to the action of nickel carbonyl and thereafter separating 1,10-dimethoxydecadiene-3,7 from the resulting reaction product.

8. A process for preparing 1,10-dimethoxydecadiene-3,7 which comprises subjecting 3-chloro-5-methoxypenten-1 to the action of nickel carbonyl at a temperature within the range of 0° C. to 150° C. and thereafter separating 1,10-dimethoxydecadiene-3,7 from the resulting reaction product.

9. A process for preparing 1,10-dimethoxydecadiene-3,7 which comprises subjecting 3-chloro-5-methoxypenten-1 to the action of nickel carbonyl at a temperature within the range of 10° to 75° C. and thereafter separating 1,10-dimethoxydecadiene-3,7 from the resulting reaction product.

10. The process set forth in claim 9 in which the quantity of nickel carbonyl employed is at least 0.5 mols per mol of 3-chloro-5-methoxypenten-1.

11. The process of claim 9 in which the reaction is carried out in the presence of an inert organic diluent.

12. The process of claim 9 in which the reaction is carried out in the presence of methanol as an inert organic diluent.
